COMPRESSOR STRUCTURE

Lindsay H. Browne, Pittsford, N. Y., assignor to
 Kellogg Compressor and Manufacturing Corporation, a corporation of New York

Application August 8, 1936, Serial No. 94,930

3 Claims. (Cl. 230—191)

This invention relates to improvements in compressor structures.

An object of the invention is to provide an improved piston structure.

5 Another object of the invention is to provide a piston and connecting rod structure suitable for use in compressors and including improved means of joining the rod and piston.

Still another object is to provide a structure 10 of the above type in which the wrist pin is secured without the use of bosses in the piston barrel, and in which working of the wrist-pin into contact with the cylinder wall is rendered impossible.

15 A further object is to provide a structure of the above character including a suction valve on the piston, the valve, piston and connecting rod being fastened together by a single securing means.

Another object is to provide an improved oil 20 baffle in the piston.

A still further object is to provide a structure of the above type which may be cheaply, easily and accurately manufactured.

Other objects and advantages of the invention 25 will become evident during the course of the following description in connection with the accompanying drawing in which:

Figure 1 is a vertical sectional view showing the piston and upper end of the connecting rod in 30 place in a suitable compression cylinder;

Figure 2 is a vertical sectional view showing the parts separated to illustrate the assembly;

Figure 3 is a side elevation of the piston barrel;

Figure 4 is a top view of the same;

35 Figure 5 is a side elevation of the ring plate valve;

Figure 6 is a plan view of the same;

Figure 7 is a detail side elevation of the connecting rod and trunnion structure; and

40 Figure 8 is a top view of the trunnion member.

Referring to Figure 1, the numeral 10 indicates a compressor cylinder carrying a discharge valve plate 11 and a cylinder head 12 superimposed on the plate, these parts being clamped together by 45 means fully described and claimed in co-pending application Serial Number 94,929, filed August 8, 1936, and comprising a clamping screw 13 in a cross yoke 14 secured to the compressor crank-case (not shown), the screw 13 engaging a ball 15 sunk into the center of the head 12. A central discharge passage 16 through the plate 11 is 50 controllable by an upwardly opening spring leaf valve 17 of a type fully described and claimed in the above-mentioned application.

55 A piston 18 is slidable in the cylinder 10 and

is adapted to be reciprocated by any suitable type of crank (not shown) through the medium of a connecting rod 19. The body of the piston consists of a cylindrical barrel 20 shown in detail in Figure 2, and having a flat head 21 pierced by a central hole 22. The outer face 23 of the head 21 has therein an annular groove 24 from which holes 25 lead into the interior of the barrel 20. A forked member 26, shown in detail in Figures 2, 7 and 8, has cylindrically curved side 10 legs 27 and 28 adapted to fit accurately in the cylindrical interior of the barrel 20. A short cylindrical boss 29 on the top of the member 26 is adapted to engage the inner face of the head 21, and a central hole 30 through the boss 29 is 15 tapped to accommodate a clamping screw 31, Figures 1 and 2.

A hollow wrist pin 32, supported in the legs 27 and 28, has rotatably mounted thereon a bushing 33 in the upper end 34 of the connecting rod 20 20 19. An oil hole 35 is provided through the top of the rod-end 34 and bushing 33. The lower end 36 of the rod 19 has secured thereto an oil splasher 37 and is lined with a bushing 38 having grooves 39 adapted to receive lubricant 25 through an inclined oil-hole 40. The upper end 34 of the connecting rod and the bushing 33 may be made with a running fit between the inner surfaces of the legs 27 and 28, the latter thus preventing side-play of the connecting rod. 30

In assembly, the member 26 is inserted in the barrel 20, the tapped hole 30 registering with the hole 22 in the piston head 21. A ring plate 41 of thin metal, shown in detail in Figures 2, 5 and 6, is placed on the flat upper face 23 of 35 the head 21 so as to overlap both the inner and outer edges of the annular groove 24. A narrow spacer washer 42, slightly thicker than the ring plate 41, and of outer diameter slightly less than the inner diameter of the ring plate, is placed 40 within the latter on the face 23. The clamping screw 31, which has a cylindrical head 43 larger than the inner diameter of the spacer washer 42, is inserted through the washer 42 and hole 22 and screwed tightly into the threaded hole 30 in the 45 forked member 26. The latter member, carrying the wrist pin 32 and attached connecting rod 19 as previously explained, is firmly clamped against the inside of the head 21, while the spacer washer 42 is clamped between the screw-head 43 50 and the face 23.

The overlapping screw-head 43 retains the ring-plate 41 on the piston, and the washer 42 acts as a concentric guide for the plate. Due to the fact that the washer 42 is slightly thicker 55

than the plate 41, the latter is allowed a small vertical play under the screw head 43. The plate thus constitutes a valve normally closing the groove 24. During the suction or the downward stroke of the piston 20 in the cylinder 10 gas passes upward through passages 44, Figure 8, between the flattened vertical faces 45 of the member 26 and the bore of the barrel 20 into the annular space 46, Figure 1, around the boss 29, from which it passes through the holes 25 into the groove 24, raising the ring plate valve 41 and entering the cylinder around the periphery of the valve.

While the ring plate valve 41 is made of thin metal, as stated, the full portage around the entire circumference of the valve allows ample valve opening within the small free rise provided by the use of the spacer washer 42, so that normally no flexing of the valve plate is necessary. The large inlet area, lightness of the valve plate and limited movement of the latter allow the valve to operate positively, quietly and with a minimum of resistance to the flow of fluid, making it especially adapted to high speed compressor operation at high volumetric efficiency.

The exact valve lift desired may readily be secured in manufacture by making the washer 42 of material thicker than the material of the ring plate valve 41 by the amount of the desired lift. It is obvious that if desired, however, the screw 31 may be made with an integral shoulder taking the place of the washer 42.

To prevent an undue amount of lubricant being carried into the inlet passage, a baffle 47, Figures 1 and 2, is disposed in a groove 48 in the lower part of the barrel 20. This baffle 47 is preferably made in the form of a disc of resilient sheet metal having a slot 49, Figure 2, to accommodate the connecting rod 19, and split at one point 50 to allow the baffle to be sprung around the rod and snapped into place in the groove 48. External oil grooves such as 51, 52 and 53 may be provided on the barrel 20, serving to regulate the supply of lubricant to the cylinder walls and to aid in sealing the piston against leakage of pressure.

From the foregoing description it is evident that the invention comprises a simple structure in which the piston, the connecting rod attaching means and the inlet valve are secured accurately in proper mutual relation by the single clamping screw 31. The individual parts are simple and lend themselves to easy and uniform manufacture by automatic or semi-automatic machinery. The barrel 20 may readily be made from bar stock or the like, due to its lack of internal bosses

or ribs, allowing the wall to be made thinner and lighter than possible in pistons wherein allowance must be made for irregularities in castings. The wrist pin 32 is retained in place without the use of the usual set-screws, lock rings or similar devices and the interposed wall of the barrel 20 makes it impossible for the wrist pin to work into contact with the cylinder wall at any time.

While the invention has been described in preferred form it is not limited to the exact structures illustrated, as various modifications may be made without departing from the scope of the appended claims.

What is claimed is:

1. In a compressor, a piston structure comprising in combination a cylindrical barrel having a head, said head being formed with inlet passages therethrough, a valve on said head adapted to control said passages, a forked member in said barrel and engaging said head, a wrist-pin in said forked member, the cylindrical wall of said barrel closely embracing the sides of said forked member whereby said wrist-pin may be retained therein, and common means to retain said valve on said head and to secure said forked member in said barrel.

2. A piston structure comprising in combination, a cylindrical barrel, a flat head on said barrel, said head being formed with an annular groove in the outer face thereof and a plurality of passages from said groove into the interior of said barrel, a ring plate valve disposed on said head and overlying said groove, a forked member in said barrel, a wrist pin in said forked member, a screw extending through said head and threaded into said forked member to secure the same in said barrel, said screw having a head overlapping the inner edge of said ring plate valve, and spacing means under said screw head and within said ring plate valve, said spacing means being thicker than said valve whereby said valve may have play between said outer face and said screw head.

3. A piston structure comprising a cylindrical barrel having an internal groove formed therein, a substantially flat head on said barrel, said head having passages therethrough, a check valve on the outside of said head and adapted to control the flow of fluid through said passages, a forked member in said barrel, a wrist pin in said forked member, common means to secure said member in said barrel and to limit the opening of said valve, and an oil baffle adapted to protect said passages, said baffle comprising a resilient member snapped into said groove.
